US00D958337S

(12) **United States Design Patent** (10) **Patent No.:** **US D958,337 S**
(45) **Date of Patent:** **** Jul. 19, 2022**

(54) **MEDICAL INFLATION DEVICE**

(71) Applicant: **Merit Medical Systems, Inc.**, South Jordan, UT (US)

(72) Inventors: **Kenneth Sykes**, Bluffdale, UT (US); **Gregory R. McArthur**, Sandy, UT (US)

(73) Assignee: **Merit Medical Systems, Inc.**, South Jordan, UT (US)

(**) Term: **15 Years**

(21) Appl. No.: **29/699,642**

(22) Filed: **Jul. 26, 2019**

(51) LOC (13) Cl. **24-02**

(52) U.S. Cl.

USPC **D24/129**

(58) **Field of Classification Search**

USPC D24/127-131, 112-114, 133, 186; 606/181, 185; 604/97.03, 98.01, 99.01, 604/264, 272, 115, 232, 187, 158, 164.08, 604/192, 263, 163, 181, 184, 198, 227; 600/101, 139, 143; 128/200.24, 207.14, 128/207.15

(57) **CLAIM**

The ornamental design for a medical inflation device, as shown and described.

DESCRIPTION

FIG. 1 is a front perspective view of medical inflation device showing our new design.

FIG. 2 is a rear perspective view thereof.

FIG. 3 is a front view thereof.

FIG. 4 is a rear view thereof.

FIG. 5 is a top view thereof.

FIG. 6 is a bottom view thereof.

FIG. 7 is a left side view thereof; and,

FIG. 8 is a right side view thereof.

The broken lines showing of parts of the drawings are included for the purpose of illustrating environment and form no part of the claimed design.

1 Claim, 6 Drawing Sheets
